UNITED STATES PATENT OFFICE.

JOHN J. McCORKELL, OF SAN FRANCISCO, CALIFORNIA.

DESIGN FOR A CANDY TRAY.

Application filed April 28, 1923. Serial No. 6,004. Term of patent 7 years.

To all whom it may concern:

Be it known that I, JOHN J. McCORKELL, a citizen of the United States, residing in the city and county of San Francisco and State of California, have invented a new, original, and ornamental Design for a Candy Tray, of which the following is a specification, reference being had to accompanying drawings, forming part thereof.

The figure is a perspective view of a candy tray showing my new design.

I claim:

The ornamental design for a candy tray as shown.

JOHN J. McCORKELL.
